United States Patent

Des. 239,911
Patented May 18, 1976

239,911

CLIP FOR WIRES OR THE LIKE

Bradley James Schmidt, East Dundee, Ill., assignor to
Illinois Tool Works Inc., Chicago, Ill.

Filed May 17, 1974, Ser. No. 471,114

Term of patent 14 years

Int. Cl. D8—08

U.S. Cl. D8—230

Fig. 1

Fig. 2

Fig. 3

Fig. 4

Fig. 5

FIG. 1 is a front elevational view showing my new design for a clip for wires or the like, the unshown back being a mirror image of the front view;

FIG. 2 is a side elevational view as viewed from the right side of FIG. 1;

FIG. 3 is a side elevational view as viewed from the left of FIG. 1;

FIG. 4 is a bottom end view of my new design shown in FIG. 1; and

FIG. 5 is a top end view of my new design shown in FIG. 1.

I claim:

The ornamental design for a clip for wires or the like, substantially as shown and described.
